UNITED STATES PATENT OFFICE.

JAMES DUNCAN, OF COSHOCOTON, OHIO.

COAL-SCUTTLE.

SPECIFICATION forming part of Letters Patent No. 325,595, dated September 1, 1885,

Application filed July 9, 1885. (No model.)

To all whom it may concern:

Be it known that I, JAMES DUNCAN, of Coshocton, in the county of Coshocton and State of Ohio, have invented new and useful 5 Improvements in Coal-Scuttles; and I do hereby declare that the following is a full, clear, and exact description thereof, reference being had to the accompanying drawings, which form a part of this specification.

10 This invention relates to certain new and useful improvements in the construction and operation of coal-scuttles such as are employed for feeding surface-burning stoves through side feed-doors, although it will be found valuable in feeding what are ordinarily termed "base-burners," which are fed at the top.

In those sections of the country where soft or bituminous coal is employed for heating purposes it is usually burned in surface-burning stoves, and in feeding the fuel through the side doors, and from the construction of the ordinary scuttles in use for that purpose, the coal is very apt to fall over the edges of the feeding platform or chute on to the floor, and as this class of coal, when handled, forms considerable "slack" or fine particles and is shoveled into the scuttles, there is a difficulty in discharging this slack into the side door of the stove without danger of soiling the floor.

30 The object of this invention is to provide a scuttle for the purpose that will prevent the coal from falling over the sides of the platform, and by means of which the slack can be fed without difficulty.

35 The invention consists in the peculiar construction of the various parts and their combinations and operation, as more fully herein-after described.

Figure 1 is a perspective view of my improved coal-scuttle. Fig. 2 is a sectional view showing the mechanism, which is partially concealed in Fig. 1.

In the drawings, A represents the body of the scuttle, and B the bail thereof, both made in the usual manner, except as is hereinafter described. The platform or chute in the ordinary scuttle is wanting in this, and its place is filled by a projecting platform, C, the sides a of which form a junction with the sides of the body, as shown, and this chute has an inclined bottom, b, which is also secured to the body, thereby forming a chute with par-

allel sides extending from near the bottom of the scuttle to its top, in front of the place usually occupied by the discharge-chute. An 55 endless conveyer, D, runs over the polygonally-shaped pulleys c, which are secured to the shafts d, one near the top of the scuttle and the other near the bottom of the chute, the ends of the shafts being suitably journaled 60 in the walls of the scuttle. One of these shafts is provided with a handle, by means of which the carrier is operated. An apron, E, is secured across the body just in rear of the conveyer, extending far enough upward to 65 hide the lower end of such conveyer. Two wings, F, curved to conform to the shape of that portion of the body to which they are attached, are pivotally secured to said body just in front of the position of the ears which carry 70 the bail. In rear of the pivotal points these wings terminate in bell-crank-shaped levers d', the free ends of which terminate in outwardly-projecting flanges so arranged that when the bail is forcibly depressed to the rear 75 it will strike such flanges and raise the wings, as shown in dotted lines in Fig. 1. These wings extend forward when depressed, so that they are concealed by the conveyer, and terminate in upwardly-projecting guards e at a 80 point immediately above the upper shaft.

In practice, when the scuttle has been filled with coal in the usual way and it is desired to discharge its contents into the stove through the side door therein, the bucket is raised to 85 the proper position, the chute presented to the open door, and the scuttle tilted in the usual way, when the bail depresses the levers and raises the wings to prevent the coal from spilling over the sides of the chute, the guards resting against the stove on either side of the door. The coal will now be discharged into the stove, leaving the slack still in the bucket and resting upon the rear face of the apron, and by 90 tilting the bucket a trifle more this slack will 95 be discharged upon the conveyer, and the operator, by rotating such conveyer, will force such slack into the stove without further trouble.

The pulleys which carry the conveyer may 100 be provided with sprocket-wheels, in which case the conveyer should be so constructed as to work with such wheels; or any other form of construction may be adopted at pleasure so

long as a conveyer is had which will perform as required.

I am aware of the Patents Nos. 119,738, 141,485, and 160,873, and make no claim to 5 the constructions shown therein as forming part of my invention.

I attach importance to my endless conveyer, for by its use I am enabled to thoroughly empty the scuttle of the slack, there being no 10 danger of any of it being carried back into the scuttle, as is apt to be the case at each return of a reciprocating slide.

I also deem it important that the wings be 15 pivoted so as to work on the inside of the scuttle, for where they work on the outside thereof, as has heretofore been proposed, the dust and fine dirt from the coal will sift through between the sides of the scuttle and the wings onto the floor; but by my arrangement the 20 dust, &c., will fall back into the scuttle.

What I claim as my invention is—

1. A coal-scuttle having an endless conveyer operating within its discharge-chute by means of a crank, substantially as and for the purpose described. 25

2. A coal-scuttle having wings pivotally secured to the sides thereof independent of the bail and working on the inside of said scuttle, combined with a bail pivoted to said scuttle and constructed to operate said wings, as and 30 for the purposes specified.

3. In combination with a coal-scuttle, wings to prevent coal from discharging over the sides of the chute, and an endless conveyer, as described, for forcing the slack coal to discharge. 35

JAMES DUNCAN.
